(57) **CLAIM**

The ornamental design for a shoe, as shown and described.

DESCRIPTION

FIG. 1 is a left side view of a shoe showing the claimed design;

FIG. 2 is a front left side perspective view thereof;

FIG. 3 is a right side view thereof;

FIG. 4 is a rear view thereof; and,

FIG. 5 is a top view thereof.

The broken lines in the figures show portions of the shoe that form no part of the claimed design.

1 Claim, 5 Drawing Sheets
